(57) **CLAIM**

The ornamental design for a cover plate for electrical devices, as shown and described.

DESCRIPTION

FIG. 1 is a perspective view of a cover plate for electrical devices showing my new design;

FIG. 2 is an outer plan view thereof;

FIG. 3 is a lateral side elevational view thereof, the opposite side being a mirror image thereof; and,

FIG. 4 is a longitudinal side elevational view thereof.

The unshown bottom of the cover plate and the unshown longitudinal side of the cover plate opposite of FIG. 4 forms no part of the claimed design. The broken line showing of the three tabs in FIG. 1 are for illustrative purposes only and form no part of the claimed design.
